SUPPORT FOR STACKED ARTICLES

Herman Carew, Easton, Pa., assignor to Individual Drinking Cup Company, Inc., Easton, Pa., a Corporation of Pennsylvania

Application January 6, 1930. Serial No. 418,812

3 Claims. (Cl. 65—61)

My invention relates to new and useful improvements in a support for a stack of nested articles and more particularly to a support for a stack of paper dishes, the principal object of the invention residing in the formation of the support in a novel manner so as to support the stack of articles with their open faces downward and in a manner to allow the removal of a single dish at a time for use with a holder which receives and supports a single dish for use.

Another object of the invention consists in providing a support which is relatively simple, light and inexpensive in manufacture, adapting the same for distribution for use at soda fountains, lunch counters and similar places where paper dishes are now in extensive use.

A further object resides in the formation of the support with a portion adapted to be received interiorly of the lowermost inverted dish thereby holding the same against collapse and preventing the admission of dirt or other foreign matter.

With the above and other objects in view, which will appear as the description proceeds, my invention consists in the novel details of construction, and arrangement of parts, described in the following specification and illustrated in the accompanying drawing, and while I have illustrated and described the preferred embodiments of the invention, as they now appear to me, it will be understood that such changes may be made as will fall within the scope of the appended claims.

In the drawing:—

Fig. 1 is a side elevation showing a stack of articles positioned on a support and the holder in position for removing the uppermost article; and

Fig. 2 shows a vertical section through the support and a portion of a stack of articles.

My improved form of support is primarily intended for use with a holder such as is illustrated and described in my copending application executed of even date, herewith, but it will be understood that it could equally as well be used for supporting slightly different forms of dishes or dishes adapted for use in different forms of holder.

When paper dishes are used at soda fountains, lunch counters or similar places, it is desirable that they be maintained in a sanitary condition and in such a manner that they may be used without delay in service. The support may be positioned upon any suitable object such as a soda fountain, counter or the like, and will support the stack of articles with their open faces

downward so as to prevent dirt or other impurities from entering the interior of the dishes. The support consists of the base portion 1 of stepped formation, the lower edge of the base being bent inwardly as shown at 2 for strengthening purposes and to provide a contact surface for engagement with the object upon which the support is positioned. Extending upwardly from the base is the tapered body portion 3 formed with the top 4 which, as shown more particularly in Fig. 2 of the drawing, is depressed to form the raised circumferentially extending peripheral edge 5 for a purpose which will be later apparent. The dishes or other articles to be positioned upon the support are shown at 6 and are each provided, at its open end or face, with an outwardly directed bead 7 and at the bottom with a circumferentially extending interior channel 8, as shown more particularly in Fig. 2 of the drawing. The side walls of the dishes or articles are shown as tapered so that the dishes are of greater diameter at the open face than at their closed or bottom ends.

At 9 I have shown a holder adapted to receive and support a single dish and for removing a terminal dish from the stack. This holder is provided with the portion 10 which normally acts as a base or support for the holder but which will be used as a hand hold or grip when the holder is in the inverted position shown in Fig. 1 for removing the uppermost dish or terminal dish from the stack. The arms 11, forming a part of the holder, are each provided, adjacent their outer ends, with an offset portion 12 forming grooves to receive the bead 7 of the dish.

In use the dishes will be supported as shown in the drawing in nested stacked formation and when a dish is to be removed from the top of the stack the holder will be inverted and positioned as shown more particularly in Fig. 1. With the holder so positioned the bead of the uppermost cup will be received in the grooves formed by the offsets 12 and when the holder is raised the uppermost dish will be removed from the stack to receive the desired material when the holder and dish are inverted. As shown more particularly in Fig. 2 of the drawing the upwardly extending tapered body portion 3 of the support will be received within the lowermost dish or article with the raised peripheral edge 5 received in the channel 8. This supports the dish or article with its side wall slightly spaced from the outer wall of the support and the bottom of the dish or article spaced slightly above the top 4 of the support. With the bot-

tom and wall of the dish or the article spaced as described there will be no possibility of the lowermost dish or article sticking to the support and the same may be readily removed when desired. It will be further seen that the succeeding dishes or cups of the stack will likewise be supported in spaced relation one relative to the other to prevent sticking. The body portion 3 of the support holds the lowermost dishes or cups against collapse and the raised edge portion 5 engages the dish at the point of its greatest strength. The beaded edge of the lowermost dish or article of the stack will be positioned slightly above the base so that the same may be removed by the holder. This is of particular advantage for it will be appreciated that if the beaded edge of the dish rested upon the base that it would be impossible to properly engage the holder therewith so that the bead would be received in the grooves formed in the arms. The support will be of neat configuration, easily cleaned, and being light may be readily moved from place to place.

Having fully described my invention what I claim as new and desire to secure by Letters Patent is:—

1. A support for a stack of tapered nested flexible cups or the like arranged in inverted position, said support comprising a base, a tapered side wall portion connecting with the base inwardly from the latter, and a closed upper end having a depressed body portion connecting with an upwardly extending peripheral flange connecting with the side wall portion, the side and closed end of the support being shaped to fit within the body portion of the lowermost nested cup, the said flange being adapted to engage the

bottom portion of the lowermost supported cup only at a point adjacent the juncture of the bottom with the side wall of the cup and thereby space the cup from the main portion of the closed end of the support and above the base 80 thereof.

2. A support for nested cups or containers while in inverted position comprising a base portion, an upwardly extending annular flange positioned inwardly from the outer edge of the base portion, and a body portion comprising a side wall tapered inwardly from its point of connection to said annular flange and terminating at its upper end in a raised portion connecting with a depressed closed end portion, the parts 85 being so constructed and arranged with respect to the containers that the lowermost of the nested containers may be received over the body portion of the support whereby the bottom wall of the container will contact with the closed end 90 of the support at the raised edge portion only and whereby the lower edge of the container will be spaced upwardly from the base of the support.

3. The combination with a tapered flexible cup or the like having a bottom portion provided with 100 an inside circumferentially extending groove set inwardly from the side wall thereof, of a support for the cup or the like when in inverted position, said support including a tapered body portion terminating in a raised circumferentially 105 extending edge adapted to be received in the groove in the bottom of the cup or the like, to position and hold the side wall of the cup or the like parallel with but spaced from the body portion of the support. 110
